W. E. Daily,
Truss Pad,
No 19,914, Patented Apr. 13, 1858.

UNITED STATES PATENT OFFICE.

WM. F. DAILY, OF BALTIMORE, MARYLAND.

TRUSS-PAD.

Specification of Letters Patent No. 19,914, dated April 13, 1858.

To all whom it may concern:

Be it known that I, Wm. F. DAILY, of Baltimore, in the State of Maryland, have invented a new and useful Improvement in 5 Truss-Pads or Supporters for Hernia or Rupture; and I do hereby declare that the following is a full, clear, and exact description of the same, reference being had to the accompanying drawings, forming a part of 10 this specification, in which—

Figure 1, is a perspective view of my improved truss pad attached to the truss, body strap or spring. Fig. 2, is a view of the 15 back of the pad. Fig. 3, is a horizontal central section of the same, supposed to be in the position used. Fig. 4, is a similar section to Fig. 3, and shows a slight modification of the pad.

Similar letters of reference in each of the 20 several figures indicate corresponding parts.

The nature of my invention consists in constructing a hollow truss pad or supporter for hernia, with a series of small perforations in its front plate and enlarged openings in its back plate so as to allow of a 25 healing substance being brought in contact with the body to aid in curing rupture, and also a perfect ventilation or healthful circulation of air through it and over or about 30 that part of the body covered by, and with which the pad or supporter comes directly and constantly in contact.

My invention also consists in attaching the pad to the main spring of the truss or 35 body strap by means of the combined agency of a groove or recess in the back of the pad, an oblong slot in the main spring and a single set screw, whereby every facility of 40 adjusting the pad speedily by simply operating one screw is afforded and at the same time a liability of the pad twisting around and rubbing avoided.

To enable others skilled in the art to make and use my invention, I will proceed to 45 describe its construction and operation more minutely.

A, in the drawings Figs. 1, 2, and 3, represents the pad, it is made hollow and of 50 hard rubber. The convex front plate α , is perforated over a greater part of its surface with small perforations c , c , as illustrated. Its flat back plate b , is also made open as at 55 c' , c' . The holes or openings c' , c' , allow of some healing substance being brought in contact with the body, and also admit air 60 into the chamber d , of the pad; and the small perforations c , c , allow the air to come

in contact with the body and cool the same, and thus keep the part pressed upon, in a healthy condition and render the wearing of 60 a truss or supporter more comfortable and pleasant. In order to attach this pad to the main spring B , of the truss body straps or spring C , I form a deep plain or dovetail groove C' , in its back-plate or side b , and 65 provide an oblong slot D , in the main spring. The parts thus constructed are placed together as shown in all the figures, and confined by a single set screw E , which passes through the slot and the center of the 70 back plate of the pad, or through said plate and a bearing formed on the inside of the same as illustrated in the several figures. This mode of attaching is very simple and cheap, and secures the pad, when only one 75 screw is used, owing to the spring being let down into the recess C , from twisting and rubbing. It also affords great facility for 80 adjustment, as only one screw requires to be operated.

What I claim as my invention and desire to secure by Letters Patent, is—

1. Constructing a hollow truss pad or supporter A , for hernia with a series of small 85 perforations c , in its front plate α , in combination with enlarged openings in its back plate so as to allow of some healing substance being brought in contact with the body and also ventilation or a perfect and 90 healthful circulation of air through it and over or about that part of the body covered by and with which the pad or supporter A comes directly and constantly in contact, substantially as set forth.

2. Attaching the pad A , to the main 95 spring of the truss or body strap C , by means of the combined agency of a recess or groove C' , in the back of the pad, an oblong slot D , in the main spring and a single set screw E , whereby every facility of adjusting the pad A , speedily, by simply operating one screw E , is afforded, and at the 100 same time a liability of the pad A , twisting around and rubbing avoided, substantially as set forth.

The above specification of my improvement in truss pads or supporter for hernia or rupture, signed by me this second day of February, 1858.

W. F. DAILY.
